UNITED STATES PATENT OFFICE.

ABRAHAM KIPNISS AND MAX PAUL NEUMANN, OF NEW YORK, N. Y., ASSIGNEES TO
BENJAMIN MARKOWITZ, OF NEW YORK, N. Y.

MACHINE FOR MAKING METAL BINDING FOR SUITCASES.

1,278,167.

Specification of Letters Patent. Patented Sept. 10, 1918.

Application filed December 7, 1916. Serial No. 135,629.

To all whom it may concern:

Be it known that we, ABRAHAM KIPNISS, a citizen of the United States, and a resident of the city of New York, in the county of 5 Kings and State of New York, and MAX PAUL NEUMANN, a citizen of the United States, and a resident of the city of New York, in the county of Queens and State of New York, have invented a certain new and useful 10 Machine for Making Metal Binding for Suitcases, of which the following is a specification.

This invention relates to machines for shaping sheet metal to a special form known 15 as "metal binding," which binding is used in the manufacture of suit cases and other receptacles.

The object is to provide a machine which will automatically bend sheet metal that is 20 fed to it, so that a satisfactory binding is quickly formed.

The invention consists of a series of pairs of rollers which are arranged to impart forward movement to a strip of sheet metal, 25 and to bend the edges thereof back nearly upon the strip. Fixed guide bars are provided, which receive the strip as it passes from between said rollers, and an oscillating bar located alongside of said guide bars, 30 serves to bend one of the bent edges of said strip upon one of said guide bars, a trip mechanism being provided which causes said movement of the oscillating bar when the end of a certain length of said strip passes 35 from said rollers to said fixed guide bars. The invention also consists of a device controlled by said trip mechanism, whereby a second strip of metal cannot be fed to said rollers while the first strip is being moved 40 forward thereby.

In the accompanying drawings:

Figure 1 is a plan view of the machine.

Fig. 2 is a side elevation.

Fig. 3 is a section on the line III—III of

45 Fig. 1.

Fig. 4 is a transverse section on the line IV—IV of Fig. 3, and showing the passage of a strip of sheet metal between a pair of feed rollers adapted for bending the edges 50 thereof to obtuse angles from the strip.

Fig. 5 shows the passage of said strip between a pair of rollers adapted for bending the edges to right angles from the strip.

Fig. 6 shows the passage of said strip be-

tween a pair of rollers adapted for bending 55 the edges to acute angles from the strip.

Fig. 7 is a transverse section on the line VII—VII of Fig. 3, and showing the passage of said strip between a pair of feed rollers adapted for bending the edges so that 60 they stand parallel with the body of the strip.

Fig. 8 is a section on the line VIII—VIII of Fig. 1.

Fig. 9 is a view similar to Fig. 8, with 65 parts shown in a different position.

Fig. 10 is a horizontal section approximately on the line X—X of Fig. 9, parts being broken away.

Fig. 11 shows the strip when moved to rest 70 in the fixed guide bars and against the oscillating bar, and mechanism for actuating the oscillating bar.

Fig. 12 is a perspective view of the strip after it is bent by movement of the oscillating bar. 75

Fig. 13 is a detail view showing the strip further bent when it has been removed from the machine and applied as "metal binding" 80 to a suit case.

Journaled in the frame 1 of the machine is a driving shaft 2 to which is secured a gear wheel 3. Gear wheel 3 is in mesh with a gear wheel 4 secured to a shaft 5 to which a roller 6 is secured. In mesh with gear wheel 4 is a gear wheel 7 secured to a shaft 8 to which a roller 9 is secured. Also in mesh with gear wheel 4 is a gear wheel 10 which is journaled on a fixed shaft 11. In mesh with gear wheel 10 is a gear wheel 90 12 secured to a shaft 13 to which a roller 14 is secured. Gear wheel 12 is in mesh with a gear wheel 15 secured to a shaft 16 to which a roller 17 is secured. 85

In mesh with gear wheel 3 is a gear wheel 95 18 secured to a shaft 19 to which a roller 20 is secured. Gear wheel 18 is in mesh with a gear wheel 21 secured to a shaft 22 to which a roller 23 is secured. Also in mesh with gear wheel 18 is a gear wheel 24 which is journaled on a fixed shaft 25. In mesh with gear wheel 24 is a gear wheel 26 secured to a shaft 27 to which is secured a roller 28. Gear wheel 26 is in mesh with a gear wheel 29 secured to a shaft 30 to which 105 a roller 31 is secured.

It will be seen that by means of the gearing described, rotation of the driving shaft

2 causes rotation of the pair of rollers 14 and 17, pair 6 and 9, pair 20 and 23, and pair 28 and 31. The upper roller of each pair is forced down upon the lower roller by means of springs 32 which bear against sliding boxes 33 in which the shafts of the upper rollers are journaled.

A strip of sheet metal 34 may be placed upon a horizontal support 35 and passed forward between lateral guides 36 and between the upper and lower rollers of each of the series of pairs, whereby forwarding movement is imparted to the strip. The rollers are shaped so that as the strip is moved forward between them, the edges of the strip are bent back to form the folds *a*.

The first pair of rollers 14 and 17 is provided with coöperating inclined surfaces 37 and 38 adapted for bending the edges of the strip to obtuse angles from the strip. The second pair of rollers 6 and 9 is provided with coöperating rectangular surfaces 39 and 40 adapted for further bending the edges of the strip to right angles therefrom. The third pair of rollers 20 and 23, is adapted for further bending the edges to acute angles from the strip, this being accomplished by means of inwardly inclined surfaces 41 formed on the upper roller 23. The fourth pair of rollers is adapted for further bending the edges so that they stand parallel with the strip, thereby forming the folds *a*. This is accomplished by means of cylindrical surfaces 42 formed on the upper roller 31, the folds *a* being forced between the guiding shoulders 43 and 44 formed on said pair of rollers.

Secured to a rock-shaft 45 journaled in the frame 1 is a lever 46 located between the first and second pairs of rollers and having a roller 47 mounted thereon which rests upon the moving strip 34, as shown in Fig. 3. Also secured to rock-shaft 45 is a long arm 46^a, the outer end of which is located between the second and third pairs of rollers, and rests upon the moving strip 34. To the arm of lever 46 opposite that on which roller 47 is mounted, is pivoted a gate 48, the outer end of which rests upon a support 49, located above the support 35. A passage 50, having a height approximately equal to the thickness of the strip 34, is left between the two supports. When the strip 34 is being fed forward by means of the series of pairs of rollers, as shown in Fig. 3, the strip serves to support the arm 46^a and the end of lever 46 carrying the roller 47 and causes the gate 48 pivoted to the opposite end of the lever to be moved across the passage 50, thereby closing the passage, whereby a strip 34 other than the one supporting the lever 46 cannot be admitted to the series of pairs of feed rollers.

To rock-shaft 45 is secured an arm 51 which is adapted for engagement with a le-

ver 52, whenever arm 46^a or lever 46 ceases to be supported by the moving strip 34. Lever 52 is pivoted at 53 to a slide 54, and is held against a fixed pin 55 by means of a spring 56. Between the pivot and the end 70 of lever 52 is a projection 57 which normally stands in the path of rollers 58 journaled on a wheel 59 secured to the driving shaft 2. The periphery of wheel 59 is provided with worm teeth 60 which engage corresponding teeth of a worm wheel 61 loosely mounted on a shaft 62.

While the moving strip 34 supports the lever 46 and arm 46^a, the rock-shaft 45 causes the arm 51 to be held out of engagement with the end of lever 52, as shown in Fig. 8. During this time the rollers 58 on wheel 59, by engagement with projection 57 on lever 52 may cause movement of the lever upon its pivot 53. In order to avoid stopping rotation of the driving shaft and feed rollers when no strips are to be supplied in the machine, arm 51 may, by means of chain 63 connected to arm 46^a and a suitable fixed support, be held out of engagement with lever 52 when no strip 34 is being moved forward by the feed rollers.

When the strip 34 is moved forward so that its rear end moves away from beneath the end of arm 46^a, the arm will drop, thereby causing movement of the rock-shaft 45, and consequent movement of gate 48 upward so that another strip may be passed through passage 50 to the feed rollers, and causing arm 51 to be moved into engagement with the free end of lever 52. Then during rotation of the wheel 59, one of the rollers 58 thereon by engagement with the projection 57 will cause movement of the end of the lever that is pivoted to the slide 54, thereby causing movement of the slide. Movement of the slide causes a spring 64 to be pressed against an arm 65 loosely mounted on the slide, until a pin 66 attached to the slide reaches the end of a slot 67 formed in the arm. Arm 65 will then be moved by the slide, and a roller 68 mounted on the arm and in engagement with an annular groove 69 formed in sliding collar 70 engaging a spline 71 on the shaft 62, causes movement of the sliding collar from the position shown in Fig. 2 to the position shown in Fig. 9. This causes teeth 72 formed on the sliding collar 70 to engage corresponding teeth 73 formed on the hub of worm wheel 61. Rotation of worm wheel 61 then causes rotation of collar 70 and shaft 62. A friction surface 74 pressed against slide 54 by means of a spring 75 serves to hold the slide and parts connected therewith at rest in the position to which they are moved.

Secured to shaft 62 is a chain-wheel 76 which drives a chain 77 causing rotation of a chain-wheel 78 and a shaft 79 secured 130

thereto. To the ends of shaft 79 are secured wheels 80 and 81, each wheel being provided with pins 82 which are placed eccentrically to the center of the wheel. The 5 pins 82 are connected by links 83 to pins 84 placed eccentrically to the center of disks 85 and 86 which are seated in annular recesses 87 formed in standards 88 secured to the main frame of the machine. The disks 10 85 and 86 are cut away in their central part, so that the strip can be moved by the feed rollers forward through the disks. The disks are connected by a bar 89 having an attached bar 90 extending radially from the 15 center of the disks. Weights 91 are attached to the bar 89, whereby rotary movement is imparted to the disks, the weights coming to rest on supports 92 and thereby causing the bar 90 to come to rest below one of 20 the folds *a* and a portion of the strip. The standards 88 are connected on the side opposite to bars 89 and 90 by means of an upper bar 93 and a lower bar 94, a passage 95 being left between them through which the 25 strip may pass. The upper bar 93 is provided with a guide 96 through which the other fold *a* may pass, and one side of the bar is shaped so that its surface 97 extends radially from the center of the disks. 30 Wheel 80 is provided with a cam surface 98 which occupies the position shown in Fig. 11 when the parts there shown are at rest. When shaft 79 and wheels 80 and 81 secured thereto are rotated, the cam surface 35 98 moves into engagement with a roller 99 journaled in a vertical sliding-bar 100, thereby causing downward movement of the bar. The lower end of bar 100 is in engagement with an arm 101 secured to a rock-shaft 102, 40 the arm being held in engagement with the bar by means of a spring 103. Secured to rock-shaft 102 is a lever 104 having an arm 105 pivoted to its outer end. Connected to arm 105 is a rod 106 which passes through 45 an eye 107 attached to lever 104. By means of a spring 108, a hook 109 forming part of arm 105 is pressed against the under side of the moving strip to the rear of the last pair of feed rollers 28 and 31. When the rear 50 end of the strip 34 shown in Fig. 3, moves past the hook 109, spring 108 causes the hook to move up behind the end of the strip. Action of the downwardly moving bar 100 on arm 101 will then cause movement of the 55 rock-shaft 102 and consequent movement of lever 104 and parts connected therewith, from the position shown in Fig. 3 to the position shown in Fig. 9, thereby causing the strip to be moved from the last pair of 60 feed rollers forward into the fixed guides 95 and 96 and to rest above the bar 90. The feed rollers have such relation to the center of the disks, that the center of the strip that is fed from the rollers stands to one side of 65 the center of the disks, in order that the

folded part *b* of the strip shown in Fig. 12 may have less length than the other part.

During the rotation of shaft 79 which causes cam 98 to actuate the vertical bar 100 and thereby cause movement of hook 109 forward and back, the eccentric pins 82 on wheels 80 and 81 will be moving over the dead center with reference to the connecting rods 83 and eccentric pins 84 of disks 85 and 86, so that there will then be practically no movement of the disks. During half of a revolution of collar 70, shaft 62, and consequent half revolution of shaft 79 and wheels 80 and 81, the disks and parts connected therewith will be moved from the position shown by full lines in Fig. 11 to the position shown by dotted lines, thereby causing the position of the strip above the bar 90 to be bent over against the incline 97 of the bar 93, whereby the fold *b* is formed. 75 A recess 110 is formed in the surface 97 for the purpose of receiving the fold *a*. Before the collar 70 reaches the end of another half of a revolution, a roller 111 journaled on the collar rides against a fixed inclined surface 80 85 112, see Fig. 10, which causes the collar to be moved out of engagement with rotating worm wheel 61, thereby stopping rotation of shaft 62 and all parts driven thereby. This movement of collar 70 will cause slide 90 95 112 and parts connected therewith to be moved to the position shown in Fig. 2 and the operations that have been described may then be repeated.

Another strip then being fed into the 100 fixed guides 95 and 96 and above the bar 90 and against the rear end of the previously bent strip, by means of the feed rollers will cause the completed product shown in Fig. 12 to be forced out of the machine. 105

In Fig. 13 is shown the manner in which the product shown in Fig. 12 is bent upon a portion 113 of a suit case.

Having described our invention, what we claim is:

1. A machine of the character described, comprising mechanism for automatically bending over the edges of a strip of sheet metal; means forming a defined path through which a portion of the strip having 110 said bent-over edges is fed, said means including a straight edge; one of said bent-over edges and a material portion of the strip protruding beyond said straight edge; means for acting upon said protruding portion of the strip comprising an oscillatable bar so placed with respect to said straight edge that the bar is adapted for bending said protruding portion of the strip over said straight edge; means for actuating said 115 oscillatable bar; and a trip mechanism adapted for controlling said means for actuating said oscillatable bar. 120

2. A machine of the character described, comprising continuously revolving rollers 130

and mechanism for actuating them, said rollers adapted for feeding strips of sheet metal forward and serving to bend the edges thereof back nearly upon the strips; guide bars placed in the path of said strips as they pass from said rollers, and spaced apart a distance equal to the thickness of said strips, and recessed to receive one of said bent edges; an oscillatable bar so placed with respect to said rollers that it is adapted for bending the other bent edge against one of said guide bars; means for actuating said oscillatable bar; and a trip mechanism adapted for controlling said means for actuating said oscillatable bar.

3. A machine of the character described, comprising continuously revolving rollers and mechanism for actuating them, said rollers adapted for feeding strips of sheet metal forward and serving to bend the edges thereof back nearly upon the strips; guide bars placed in the path of said strips as they pass from said rollers, and spaced apart a distance equal to the thickness of said strips, and recessed to receive one of said bent edges; an oscillatable bar so placed with respect to said rollers that it is adapted for bending the other bent edge against one of said guide bars; the center about which the oscillatable bar moves being located to one side of the center of the strip.

4. A machine of the character described, comprising continuously revolving rollers and mechanism for actuating them; said rollers adapted for feeding strips of sheet metal forward and serving to bend the edges thereof back nearly upon the strips; means forming a defined path through which one bent edge and a portion of the strip having said bent-over edges is fed, said means including a straight edge; an oscillatable bar so placed with respect to said straight edge that the bar is adapted for bending the other portion of the strip and bent edge over said straight edge; means for actuating said oscillatable bar, said means including a trip mechanism which is controlled by passage of said strip between said feed rollers in such a manner that the trip mechanism becomes operative when said strip is moved away from said feed rollers.

5. A machine of the character described, comprising continuously revolving rollers and mechanism for actuating them, said rollers adapted for feeding a strip of sheet metal forward and serving to bend the edges thereof back nearly upon the strip; a trip mechanism which is held out of action by means of said strip; a movable gate controlled by said trip mechanism, which will prevent a second strip of sheet metal from being fed to said rollers; means forming a defined path through which one bent edge

and a portion of the strip having said bent-over edges is fed, said means including a straight edge; an oscillatable bar so placed with respect to the said straight edge that the bar is adapted for bending the other portion of the strip and bent edge over said straight edge; means for actuating said oscillatable bar; said trip mechanism being set into action by passage of said strip away from said feed rollers and arranged to cause operation of said means for actuating said oscillatable bar.

6. A machine of the character described, comprising continuously revolving rollers and mechanism for actuating them, said rollers adapted for feeding strips of sheet metal forward, and serving to bend the edges thereof back nearly upon the strips; means forming a defined path through which one bent edge and a portion of the strip having said bent-over edges is fed, said means including a straight edge which is located to one side of the center of the strip; an oscillatable bar so placed with respect to said straight edge that the bar is adapted for bending the other portion of the strip and bent edge over said straight edge; means for actuating said oscillatable bar; and a trip mechanism adapted for controlling said means for actuating said oscillatable bar.

7. A machine of the character described, comprising continuously revolving rollers and mechanism for actuating them, said rollers adapted for feeding a strip of sheet metal forward and serving to bend the edges thereof back nearly upon the strip; a trip mechanism which is held out of action by means of said strip; devices controlled by said trip mechanism and adapted for imparting further forward motion to said strip as it passes from between said feed rollers; means forming a defined path through which one bent edge and a portion of the strip having said bent-over edges is fed, said means including a straight edge; an oscillatable bar so placed with respect to said straight edge that the bar is adapted for bending the other portion of the strip and bent edge over said straight edge; means for actuating said oscillatable bar, said means being controlled by said trip mechanism; said trip mechanism adapted to be set into action by passage of said strip away from said feed rollers and then causing action of said devices for imparting further forward movement of said strip, and causing said oscillating bar actuating means to be actuated.

Signed at New York city in the county of New York and State of New York this 29th day of November, A. D. 1916.
